DESIGN FOR A FUEL DISPENSER UNIT

Warren H. De Lancey, Springfield, and Bertram P. Pond, Longmeadow, Mass., assignors to Engineering Products, Inc., Springfield, Mass., a corporation of Massachusetts

Application July 11, 1947, Serial No. 140,224

Term of patent 3½ years

(Cl. D52—2)

To all whom it may concern:

Be it known that we, Warren H. De Lancey and Bertram P. Pond, both citizens of the United States, said De Lancey residing at Springfield, in the county of Hampden and Commonwealth of Massachusetts, and said Pond residing at Longmeadow, in the county of Hampden and Commonwealth of Massachusetts, have invented a new, original, and ornamental Design for a Fuel Dispenser Unit, of which the following is a specification, reference being had to the accompanying drawings forming part thereof, in which:

Fig. 1 represents a front perspective view of a fuel dispenser unit showing our new design.

Fig. 2 represents a rear perspective view of the unit shown in Fig. 1.

Fig. 3 represents a top plan view of the unit disclosed in Fig. 1.

Fig. 4 represents a right-hand side view of the unit disclosed in Fig. 3.

We claim:

The ornamental design for a fuel dispenser unit, as shown.

WARREN H. DE LANCEY.
BERTRAM P. POND.
